UNITED STATES PATENT OFFICE.

WILLIAM W. LASKER, OF BROOKLYN, NEW YORK, ASSIGNOR, BY MESNE ASSIGNMENTS, TO REMINGTON RAND INC., OF NEW YORK, N. Y., A CORPORATION OF DELAWARE.

ADDING-SECTOR-RESTORING MECHANISM.

Application filed November 24, 1925, Serial No. 71,192.

The present invention relates to printing tabulators for statistical purposes and more particularly to a means for restoring the adding sectors from carry position to zero or normal position.

Generally considered, the device of the present invention is applicable to tabulator printers of the character shown in U. S. Letters Patent No. 1,245,502, to which reference can be had for details of the function and operation of the adding sectors. In this patented construction the adding sectors are set in position when a carry is necessary, by the accumulator wheels upon the return stroke of the sectors after each printing operation set-up, and then must be cleared to zero before the total taking stroke takes place when the sectors roll out the accumulation on the printing set-up stroke. In machines of the character in use heretofore this clearing or resetting of the adding sectors to zero takes place under control of a space card which must run through the analyzing unit ahead of the total card.

Some of the objects of the present invention are to provide an improved means for clearing and restoring adding sectors of tabulating or kindred machines to normal or zero position; to provide means for taking a total automatically and directly following the last card of a group to be added; to provide means for eliminating the use of an extra card for total taking purposes; to provide means whereby the number of card cycles is reduced in the addition of and total taking of perforated data on a group of cards; and to provide other improvements as will hereinafter appear.

In the accompanying drawings Fig. 1 represents a detail in side elevation, with parts broken away, of an adding sector and its adjuncts having a sector clearing and total taking mechanism embodying one form of the present invention; Fig. 2 represents a sectional detail of an automatic latch control for a cam operated part; Fig. 3 represents a fragmentary elevation of an adding sector in zero position and the operating parts for returning the sector to such position; Fig. 4 represents a similar elevation to Fig. 3 with an adding sector in position; Fig. 5 represents a fragmentary portion of the machine in part section showing the position of the parts with the total pin in analyzing

relation to the total card; Fig. 6 represents a perspective of the total operating lever casting; and Fig. 7 represents a detail in plan of the control cams.

Referring to the drawings, one form of the present invention is shown applied to an adding sector 10 which forms one of a series of sectors in a unit for setting type sectors in printing position according to perforations in record cards which control the action of the sectors 10. Each sector 10 is mounted for rocking movement on a pivot 11 and controls the position of its type sector 12 so that the type 13 are respectively located in printing position with respect to the paper 14 and platen 15. Connection between each adding sector 10 and its type sector 12 is by way of a lost motion slot 16 and a pin 17, while a spring 18 is normally under tension to project both sectors toward the type setting position. A spring 20 is stretched between the two sectors so that the type sector 12 is held pressed to its initial position while the adding sector 10 is under tension to complete its carry operation and come to rest, when released for carry, one tooth behind the zero position. When such adding sector 10 is not to function for a carry operation, it is held and limited in its return movement by a pin 21 laterally projecting from the sector 10 and abutting the end of the hook 22 of a bar stop 23 which is provided with a totaling abutment spur 24 located in the path of movement of the carry lug 25 on the accumulator wheel 26 of the next lower order. Thus, when the accumulator wheel of the next lower order reaches the position to carry over, its lug 25 engages the spur 24 of the adjacent adding sector of higher order and lifts the bar stop 23 so that the sector pin 21 registers with the slot portion of the hook 22. This allows the adding sector 10 to travel one tooth farther than normally and so actuate the accumulator wheel which it controls.

The adding sectors are each normally held in zero position by a shutter 27 having a zero stop 28 in the path of the sector heel 29, and the shutters are released for operation by rocking them to one side as well understood in the art.

In order to restore all of the adding sectors 10 to zero position prior to the total taking cycle, a bail 30 (Figs. 1, 3 and 4), is

arranged transversely of the machine and is carried at its ends by rock arms 31 so that its path of movement intercepts all of the sectors which are in carry position and its length of travel is such as to bring such sectors back to zero position abutting the shutter zero stops 28 and releasing the bar stop 23 so that it drops to bring its hook end into register with the pin 21. The arms 31 are journalled on suitable standards 32 (only one being shown) and an operating rod 33 pivoted thereto is pivotally connected at 34 to one end of an operating lever 35, which is pivoted to a bracket 36, (Fig. 3), and has its other end provided with a roller 37 travelling in a cam groove 38 of an actuating cam 40 mounted on the action shaft 41. The bracket 36 also serves as a pivotal support for a rock lever 42, the function of which will presently appear. Thus at the end of a group tabulation the initial step in the total taking cycle brings the cam 40 to a position (Fig. 3), where its rise causes the lever system to rock the bail 30 to return all adding sectors, which have just functioned in a carry operation, to initial or zero position so that all sectors in the unit will have a common starting position for rolling out the accumulated total.

30 For the purpose of ensuring the removal of all accumulator wheels 26 from their respective adding sectors 10 before any reset movement of the latter takes place the accumulator control cam 43, by which the accumulator wheels of the several units are thrown into and out of mesh with the sectors 10, is positively shifted to unmeshing position by the rock lever 42 transmitting motion through a link 44 to the cam 43, where- 40 by the latter is shifted clockwise, as seen in Fig. 3, to thereby cause the accumulator wheels to be removed from the sectors 10. The rock lever 42 is operated only at the time a total is to be taken and remains idle at 45 other times so that the control cam 43 is automatically thrown into and out of mesh with the adding sectors by the action of the accumulator link 45 under the control of the oscillating crank sector cam 46. This inter- 50 mittent action of the rock lever 42 is effected in the present instance by the provision of a second cam 47 keyed to the action shaft 41 and provided with a cam groove 48 fac- 55 ing the free end of the rock lever 42. This end of the rock lever 42 is provided with a capped bushing 50, (Fig. 2), which receives a plunger 51 normally under pressure of a coil spring 52 having a tendency to eject the plunger toward the groove 48 and with which it is normally in alinement. The end of the plunger 51 is provided with a circumferential groove or shoulder 53 for coaction with a pivoted latch 54 which is normally held pressed toward said latching groove 53 by 60 a spring 55 stretched between a lug 56 on

the latch 54 and a lug 57 on the rock lever 42. Normally, the latch 54 is held by its spring 55 seated in the groove 53 so that the plunger 51 is held out of the groove of its cam 47 but provision is made for releasing the latch 54 at the proper time in the cycle of operations leading up to the total taking, so that the plunger 51 enters the cam groove 48 and comes under its control to actuate the rock lever 42 at the proper time. 75 As soon as the rock lever has completed its control movement the plunger 51 is automatically ejected from the cam groove 48 by the inclined face of a block 58, (Fig. 1), located in the groove 48 and acting to return the plunger to latching engagement with the latch 54. The releasing of the latch 54 from its plunger 51 takes place in timed relation by the provision of a link 60 connected at one end to the latch and at its other end to a bell crank 61 which is pivoted at 62 to a fixed part and has its opposite end provided with a pin 63.

For operating the bell crank 61 at the proper time in the cycle of total taking, the pin 63 is so located that in total operating position of a reciprocable link 64 it is in the path of movement of a lug 65 fixed to the link 64, and therefore receives motion transmitted from the link 64. The link 64 is pivoted at 66 to one arm of a pivoted bell crank 67 and has bearing lugs 68 at one end to receive a rod 69 which is also connected to the pivot 66. This rod 69 passes through a hole 70 in the lower extremity of a total pin 71 and it is the function of this pin 71 to so vary the position of the link 64 as to determine its connection to parts operated thereby. When the total pin 71 moves upward under the action of its spring, it carries the rod 69 with it, and since the latter is pivoted at 66 and is also fast to the link 64, the last named will also be swung around the pivot 66 and thus bring the lug 65 to a different position. Motion is transmitted to the bell crank 67 by a roller 72 carried by its operating arm 73 and riding in a cam groove 74 of a cam 75 on the main shaft 76 of the machine. In addition to causing operation of the bell crank 61 the reciprocation of the link 64 also transmits motion to an arm 77 of a casting 78 pivoted upon a shaft 80 and having an arm 81 arranged when operated to snap past and be held by a pivoted latch 82 which is normally urged toward latching position by a spring 83. The free end of the latch 82 has a projecting lug 84 arranged in latching position to extend into the path of a trip 85 carried by the cam 75. Motion is transmitted to the arm 77 by a pin or lug 86 projecting from the link 64 and so located as to intercept a pin 87 on the arm 77 when the link 64 is placed in total taking position. Under all operating conditions except the total taking one, the link 64 reciprocates the lugs 65 and 86 in a path which does 130

not intercept the respective pins 63 and 87 and consequently no motion is transmitted to the arm 77 or to the bell crank 61. When a total is taken, however, the total pin 71 is restricted in its movement by the punched total card and thereby shifts the link 64 so that its lugs 65 and 86 reciprocate to engage the respective pins 63 and 87.

The rocking movement of the casting 78 is transmitted by an arm 90 and a connecting rod 91 to a crank 92 on the total taking shaft 93. A latch lug 94 (Fig. 6) is provided on the arm 81 of the casting 78 for engagement by the latch 82 in order to hold the total shaft 93 in total taking position for the proper carrying out of the total cycle. When the trip 85 on the cam 75 picks up the latch 82, the total taking shaft 93 and its associated parts are released for return to initial and idle position.

In order to restore the sectors following the setting and printing operations a restoring bar 95 (Figs. 1, 3 and 4) is mounted between two end restoring frames 96 and extends transversely across the front edges of the type sector arms 97. The frames 96 are pivoted on the pivot 11 which also serves as the bearing support for the type sector arms 97. The movement of the restoring frames 96 takes place through a cam roller 97 mounted upon one frame 96 and operatively located in a cam slot 98 of a cam member 100 which is pivoted on a rod 101 to swing in the desired arc to cause the actuation of the restoring frame. The cam slot 98 is provided with a dwell 102 which causes the proper timed rocking of the restoring bar 95 and also provides for holding the sectors from forward movement for the period when the accumulator wheel gears are disengaged to clear the machine and reengaged to roll out the accumulation for the total. An operating link 103 connects the cam member 100 with a crank sector 46 fixed to the actuating shaft 105 of the machine, the said sector 46 also serving to rock and control the accumulator cam 43 as will be understood by reference to U. S. Letters Patent No. 1,388,271 wherein the construction and operation of the accumulator wheels 26 is shown and described and need not be here repeated since this forms no part of the present invention.

In the operation of the machine the printing sectors and associated parts are operated for printing the data by control pins passing through the perforated card to position the sectors so that the selected type are in position to print upon the platen and the recorded amounts are accumulated for a total by the timed swinging of the crank sector 46 to move the accumulator wheel gears into mesh with the toothed sectors on their return movement and to remove the accumulator wheel gears on the forward stroke of the same toothed sectors. The operation of the crank

sector 46 also causes the restoring frame to operate in the desired manner to bring the printing sectors back to their zero position. When an accumulator wheel has been rotated to the carry-over position its lug 25 engages the spur 24 of the bar stop 23 which causes the hook 22 to be raised so that the lug 25 on the adding sector of the next higher order can move into the slot of the hook and thereby permit the adding sector to travel one tooth farther than under normal conditions so that the corresponding accumulator wheel moves one digit's distance. It will therefore be evident that those adding sectors which are in carry position back of the zero position must be reset to zero before the sectors move to roll out the accumulation on the accumulator wheels.

When a total is to be taken the analyzing unit comes into analyzing relation with respect to the total card which is at the end of the group being tabulated and this total card allows the total pin 71 to move upward until its collar 71' contacts with the card and in this position of the total pin the connected reciprocable link 64 has been moved to the position where the pin 63 is in the path of movement of the link lug 65 and the pin 87 on the arm 77 is also in the path of the lug 86 on the link 64 and consequently the movement of the link 64 is transmitted to both the bell crank 61 and to the arm 77, and it will thus be seen that two distinct operations are set into motion by the actuation of the link 64. The operation which shifts the arm 77 causes the connecting rod 91 to actuate the total taking shaft 93 to cause the total taking operation. The shifting of the bell crank 61 raises the latch 54 to thereby release the plunger 51 so that it enters the cam groove 48 and throws its rock lever 42 under cam control, and as this is rocked the accumulator wheel cam 43 is operated in the direction to remove the accumulator wheels from meshing engagement with the adding racks. Operating in timed relation with this removal of the accumulator wheels the cam 40 causes the operating lever 35 to be rocked in a clockwise direction to shift the bail 30 counterclockwise and return the adding sectors to zero position which thus clears the machine for the total stroke of the adding sectors. The timing of the operation of the parts is such that the inclined face of the block 58 releases the plunger from the cam groove 48 so that the accumulator wheel cam is again free to be operated by its normal control by the crank sector 46. The crank sector 46 at this part of the cycle is in a position holding the restoring frame actuating cam in a position to hold the sectors from forward movement and they are so held not only during the time the gears are disengaged but until the crank sector 46 has shifted the accumulator wheel cam to the position where the accumulator wheels are in mesh with the toothed sectors and at this time all of the sec-

tors are ready to make the forward stroke for rolling out the accumulation and bringing the type into position to print a total.

From the foregoing it will be apparent that the taking of totals by card controlled tabulating machines has been greatly simplified and the card group totals are taken automatically without interposed steps in preparation for taking the total. By the mechanism of the present invention it is now unnecessary to provide a clearing card in advance of the total card and the time heretofore consumed in properly placing such space or clearing cards in the respective groups is saved. Incidental to thus dispensing with the clearing cards is the elimination of errors heretofore present due to placing the clearing cards at the wrong place in the group of cards so that the machine is either cleared prematurely or the total cycle takes place without clearing and an incorrect total results. When only total cards are required for each group and as these are respectively located as the last or bottom card of the groups errors due to misplacement are reduced to a minimum and in practice seldom if ever occur.

Having thus described my invention, I claim:

1. In a machine of the character stated, the combination of an accounting printing mechanism, an accumulator unit arranged to engage said printing mechanism, a total operating means, a clearing device for said mechanism, common means for actuating said clearing device and said total operating means, and means including a cam controlled part for holding said accumulator unit out of engagement with said printing mechanism during the operation of said clearing device.

2. In a machine of the character stated, the combination of an accounting printing mechanism, an accumulator unit arranged to engage said printing mechanism, a total operating means, a clearing device for said mechanism, common means for actuating said clearing device and said total operating means, and means controlled by said common means for holding said accumulator unit out of engagement with said printing mechanism during the operation of said clearing device.

3. In a machine of the character stated, the combination of an accounting printing mechanism, an accumulator unit arranged to engage said printing mechanism, a total operating means, a clearing device for said mechanism, common means for actuating said clearing device and said total operating means, a rotatable cam, a lever connected to said accumulator unit and normally disconnected from said cam, and means operated by said common means for causing said cam to engage said lever whereby said accumulator unit is held out of engagement with said printing mechanism during the operation of said clearing device.

4. In a machine of the character stated, the combination of an accounting printing mechanism, an accumulator unit arranged to engage said printing mechanism, a total operating means, a clearing device for said mechanism, common means for actuating said clearing device and said total operating means, a rotatable cam, a lever connected to said accumulator unit, a cam roller carried by said lever, a spring pressing said roller to engagement with said cam, a latch normally holding said roller out of engagement with said cam, and means operated by said common means for releasing said latch whereby said cam causes said lever to hold said accumulator unit out of engagement with said printing mechanism during the operation of said clearing device. 75

5. In a machine of the character stated, the combination of an accounting printing mechanism, an accumulator unit arranged to engage said printing mechanism, a total operating means, a clearing device for said mechanism, common means for actuating said clearing device and said total operating means, a rotatable cam, a lever connected to said accumulator unit, a cam roller carried by said lever, a spring pressing said roller to engagement with said cam, a latch normally holding said roller out of engagement with said cam, and means for releasing said latch whereby said cam causes said lever to hold said accumulator unit out of engagement with said printing mechanism during the operation of said clearing device. 80

6. In a machine of the character stated, a carry sector arranged to come to rest at one side of its normal zero position after a carry operation, a clearing device arranged to engage said sector to restore it to zero position, an accumulator unit operatively mounted with respect to said carry sector, a total operating means, and means controlled by a total card for holding said accumulator out of engagement with said sector; operating said clearing device, and causing said total operating means to function. 90

7. In a machine of the character stated, a carry sector arranged to come to rest at one side of its normal zero position after a carry operation, a clearing device arranged to engage said sector to restore it to zero position, an accumulator unit operatively mounted with respect to said carry sector, a total operating means, and means controlled by an analyzing total pin for holding said accumulator out of engagement with said sector; operating said clearing device; and causing said total operating means to function. 100
